UNITED STATES PATENT OFFICE

93,767

DESIGN FOR A GAME APPARATUS

David Gottlieb, Chicago, Ill.

Application February 23, 1934, Serial No. 50,832

Term of patent 3½ years

To all whom it may concern:

Be it known that I, DAVID GOTTLIEB, a citizen of the United States, residing at Chicago, in the county of Cook and State of Illinois, have invented a new, original, and ornamental Design for a Game Apparatus, of which the following is a specification, reference being had to the accompanying drawing, forming part thereof, and in which the single figure is a perspective view of a game apparatus showing my new design.

I claim:

The ornamental design for a game apparatus, as shown.

DAVID GOTTLIEB.
